UNITED STATES PATENT OFFICE.

GRACE P. BROWN, OF NEW YORK, N. Y.

DESIGN FOR A BICYCLE OR SIMILAR STOCKING.

SPECIFICATION forming part of Design No. 29,087, dated July 19, 1898.

Application filed December 1, 1897. Serial No. 660,452. Term of patent 3½ years.

To all whom it may concern:

Be it known that I, GRACE P. BROWN, a citizen of the United States, and a resident of New York, in the county of New York and 5 State of New York, have invented and produced a new and original Design for Bicycle, or Similar Stockings, of which the following is a specification.

My design for a bicycle or similar stocking 10 is shown in the accompanying drawing, which shows the stocking in side elevation.

The design consists of a plain leg portion C, a plain extension top A, and a narrow clockwork stripe B, located, as shown in the drawing, intermediate between the two, above 15 the calf portion of the leg, at the place occupied by the roll or cuff in ordinary bicycle-stockings. D is the foot portion.

What I claim is—

The design for a bicycle or similar stocking, 20 substantially as shown and described.

In testimony that I claim the foregoing as my invention I have signed my name, in presence of two witnesses.

GRACE P. BROWN.
